UNITED STATES PATENT OFFICE.

OLIVER D. COLLIS, OF CLINTON, IOWA.

FEEDING HOPPER.

Application filed May 31, 1921. Serial No. 473,722.

To all whom it may concern:

Be it known that I, OLIVER D. COLLIS, a citizen of the United States, residing at Clinton, in the county of Clinton and State of Iowa, have invented certain new and useful Improvements in a Feeding Hopper, of which the following is a specification.

This invention relates to a collapsible container adapted specially to receive dry feed material, such as mash feed or dried buttermilk.

An exemplification of my invention is shown in the accompanying drawings in the manner following:

15 Figure 1 represents a blank from which the container is made;

Fig. 2 is a similar view of the partition member that is introduced into the container;

20 Fig. 3 is a central longitudinal section through the container;

Fig. 4 is a transverse section taken on line 4—4 of Fig. 3; and

25 Fig. 5 is a perspective view of the container ready for use as a feeding hopper.

The present container may conveniently be formed of any suitable material, such as card board or the like, the blank shown in Fig. 1 comprising a section A for the front, 30 a section B for one side, a section C for the back, and two other sections D and E adapted when overlapped to form the opposite side. Extending beyond one end of each of the sections just noted are the usual 35 flaps or wings F¹—F⁵, other similar flaps or wings G¹—G⁵ being extended from the opposite ends thereof. When properly folded upon each other in the manner common to collapsible containers, I provide a structure 40 of the kind that is shown in Fig. 5. The overlapping sections D and E and the overlapping flaps may be caused to adhere together by any of the usual methods.

45 It will be noted further that in the front wall of the container is a rectangular space H marked off by perforations or scorings in such a manner as to facilitate its being punched out by hand to provide an opening into the hopper. Preliminary to the container being used as a hopper, this section H should preferably remain in place, but thereafter it may be punched out to form an opening 9 such as is indicated in Figs. 3, 4, and 5. Also in the rear side of the carton 55 is an opening I which by preference is reinforced with an eyelet 10, the inner side of

this opening being shown as covered by a paper slip 11 or other easily breakable material. Prior to the time that the package is to be used as a hopper, this paper cover 60 is kept intact to provide a seal, but thereafter may be broken with the aid of any small instrument so as to permit the eyelet to engage with a hook or other suitable device for suspending the hopper at any convenient height.

A container so constructed may function as a hopper by providing a partition therein consisting of four interconnected sections 15, 16, 17, and 18 (see Fig. 2), the last of 70 which is adapted to lie upon the bottom of the container as shown in Fig. 3. The first and third of these sections each present one edge adjacent the inner side of the front wall A, one slightly above and the other slightly below the opening 9 which is formed by removal of the section H. The two sections 15 and 17 are, moreover, obliquely inclined, one downwardly and the other upwardly, with the intermediate section 16 in 75 substantially parallel relation to the front and rear walls of the container. By preference end flaps 15^a, and 15^b, 16^a and 16^b, and 17^a and 17^b are formed on each of the first three sections noted, so that when turned 80 to right angular position, as shown, they may lie snugly against the end walls B and D of the container. To secure the partition in place, a flap 19 is formed at the forward edge of the section 15, this latter flap being 85 connected to the front side A of the container by any suitable means, such, for instance, as by the use of an adhesive.

90 Formed in the section 17 are a plurality of openings 20 which initially may be sealed by the use of thin paper, or, if desired, the outlines of these openings may be perforated, permitting the center portion to be punched out whenever required. When this is done, the feeding material contained within the 95 hopper will be exposed at these openings. A construction such as is herein shown is particularly suitable for holding buttermilk, which is a dry flaky food much used for feeding poultry. A carton containing such a food will last for a considerable time, as it is very rich in nourishment and a little goes a long way.

100 The invention herein described is advantageous in that it may be inexpensively produced, the cartons being collapsible to occupy reduced space for shipping. When set

up, and filled with powdered buttermilk, the overlapping flaps may be connected in any convenient manner as by stapling, and this will be sufficient to prevent leakage of the 5 contents. The fastening of the partition within the carton may also be accomplished in a very simple manner, a staple or adhesive connecting the flaps 16^a and 16^b to the proximate walls being usually sufficient.

10 When secured in place in some such manner, the partition acts to tie together the opposite side walls of the carton, thus reinforcing the same and preventing damage to its contents during shipping or at other 15 times.

I claim:

1. A collapsible container of the kind described, made from a single blank so formed as to provide a boxlike structure having in 20 one of its walls an opening, and a partition within the structure arranged rearwardly of the opening and formed to provide a wall which is downwardly inclined from above the opening, also a second wall which is substantially parallel therewith, and also a 25 third wall which is upwardly inclined from below the opening, there being smaller openings in the third wall through which may be extracted loose material which lies close to the bottom of the container, substantially as described.

2. A collapsible container of the kind de-

scribed, made from a single blank so formed as to provide a boxlike structure having in 35 one of its walls an opening, and a partition arranged within the container rearwardly of the opening, extending between the walls adjacent to the sides thereof, and connected with the wall in which said opening is formed both below and above the opening, there 40 being formed in the partition other openings of smaller size through which a limited amount of loose material may be extracted, substantially as described.

3. A container of the kind described for 45 loose feeding material consisting of a boxlike structure having in one of its walls an opening, a partition within the container comprising five interconnected sections one 50 secured to the container wall above the opening, the next slanted rearwardly and downwardly therefrom, the third disposed parallel to the opening and rearwardly thereof, the fourth slanting downwardly and forwardly toward the wall beneath the opening, and the fifth disposed immovably upon the 55 bottom of the container to definitely fix the positions of the others, there being openings in the fourth section through which feeding material may be extracted substantially as 60 described.

OLIVER D. COLLIS.
